UNITED STATES PATENT OFFICE

170,364

HEATING STOVE

Chester C. Perry, Chagrin Falls, Ohio, assignor to
Perfection Stove Company, Cleveland, Ohio, a
corporation of Ohio

Application January 25, 1952, Serial No. 18,222

Term of patent 14 years

(Cl. D81—19)

To all whom it may concern:

Be it known that I, Chester C. Perry, a citizen of the United States, residing at Chagrin Falls, in the county of Cuyahoga and State of Ohio, have invented a new, original, and ornamental Design for a Heating Stove, of which the following is a specification, reference being had to the accompanying drawing, forming part hereof.

Fig. 1 is a front elevational view of a heating stove showing my new design;

Fig. 2 is a plan view of the same;

Fig. 3 is a right hand side elevational view of the heating stove, and

Figs. 4 and 5 are sectional views through the front portion of the stove, the planes of the respective sections being indicated by the lines 4—4 and 5—5 of Fig. 1.

The side of the heating stove opposite that shown in Fig. 3 is identical with the one illustrated in said view with the exception of the closure and its knob that are indicated in dotted lines in Fig. 3.

The essential features of the design are illustrated in full lines.

I claim:

The ornamental design for a heating stove, substantially as shown and described.

CHESTER C. PERRY.
